UNITED STATES PATENT OFFICE

2,187,986

RADIO TUNING SYSTEM

Cyrus T. Read, Chicago, Ill.

Application November 10, 1938, Serial No. 239,738

10 Claims.

(Cl. 74—10)

The invention relates to improvements in radio tuning systems and has for its primary object the provision of an improved system of the character indicated which is of simple construction and highly efficient in use.

Another object of the invention is the provision of an improved tuning system of the character indicated so constructed and arranged as to permit of the ready tuning of the system by 10 a minimum of manipulations.

Another object of the invention is the provision of an improved system of the character indicated which may be readily mounted in operative relation with the adjustable parts of the 15 system and readily connected therewith without disturbing the positions of said parts.

Other objects will appear hereinafter.

The invention consists in the combinations and arrangements of parts hereinafter described and 20 claimed.

The invention will be best understood by reference to the accompanying drawing forming a part of this specification and in which

Fig. 1 is a front view of a tuning system embodying the invention;

Fig. 2 a rear view of the same;

Fig. 3 a section taken substantially on line 3—3 of Fig. 1;

Fig. 4 an enlarged partial detail view of a 30 rotatable adjusting member employed in the system;

Fig. 5 a section taken substantially on line 5—5 of Fig. 4; and

Fig. 6 a section taken substantially on line 35 6—6 of Fig. 4.

The embodiment of the invention illustrated in the drawing comprises a suitable support 10 having adjusting shafts 11, 12 and 13 rotatably mounted thereon as shown. The said adjusting 40 shafts carry the adjustable parts of radio tuning condensers 14 arranged as indicated on the rear side of the support 10 to be connected in the usual way in the radio circuit, the form of apparatus illustrated being designed and intended especially for use in conjunction with radio transmitting systems or circuits. The shafts 11, 12 and 13 carry, respectively, operating or driving pulleys 15, 16 and 17 secured thereto as shown. An operating belt 18, in the form of a flexible 50 strip of thin steel, is wrapped around the pulley 15, anchored thereto by means of a pin 19 and has one of its ends connected with a tension spring 20, as shown. A similar steel belt 21 is wrapped around the pulley 16, anchored thereto by means of a pin 22 and has its end connected

with a tension spring 23. A similar steel belt 24 is wrapped around the pulley 17, and anchored thereto by means of a pin 25. Another belt 26 is wrapped around said pulley 17, anchored thereto by means of a pin 27 and has its end connected to a tension spring 28. By this arrangement means are provided whereby the adjustable elements of condensers 14 may be simultaneously moved or adjusted by pulling on the ends of belts 18, 21, and 24, and said condenser elements automatically returned to initial positions by the action of the tension springs 20, 23 and 28, as will be readily understood.

Another adjusting shaft 29 is mounted on the support 10 and provided at its rear portion with 15 a pair of switch arms 30 cooperating with pairs of electric contacts 31, 32, and 33 respectively, for the induction coils 34, 35 and 36 of the tuning system. At its front end the switch shaft 29 carries an operating pulley 37 to which an 20 operating belt 38 is anchored by a pin 39 and another spring connected belt 40 is anchored by pin 41, the free end of the belt 40 being connected as shown with a tension spring 42. By 25 this arrangement, the switch shaft 29 will be normally and yieldingly held in an initial position by means of the spring 42 but is free to yield under tension on the belt 38 so as to swing the switch arms 30 into and out of contact with the different pairs of coil contacts 31, 32 and 33, 30 as will be readily understood.

A vertical guide bar or post 43 is arranged as shown at one side of the support 10 being secured thereto by means of supporting screws 44. An operating plunger 45 is slidably mounted 35 as shown on the guide post 43, being slotted as shown in Fig. 4 to pass freely over the screws 44 during sliding operations. As best shown in Figs. 1 and 4, the ends of the belts 18, 21, 38 and 24 are passed over suitable guide pulleys 40 as indicated and brought into superposed relation against one side of the plunger 45, said plunger 45 being provided with a plurality of cross straps 46, 47, 48 and 49 embracing the ends of said belts as shown. The ends of the belts 24, 38, 21 and 18, respectively, are provided with stops 50, 51, 52 and 53 adapted and arranged to engage the under sides of the cross straps 46, 47, 48 and 49 when the plunger 45 is depressed. The plunger 45 is provided with a 45 push rod 54 projecting from the top of the support 10 and by means of which said plunger may be depressed when desired. By this arrangement, by depressing the push rod 54, all 50 of said belts 24, 38, 21 and 18 will be corre- 55

spondingly depressed through the engagement of the cross straps 46, 47, 48 and 49 with the stops 50, 51, 52, and 53 on the ends of said belts. Obviously, when the pressure on push rod 54 is released all of said belts will tend to return to initial positions under the influence of the respective springs 28, 42, 23 and 20, and the adjustable condenser members and switch arms 30 will be correspondingly moved toward initial positions by the action of said springs.

A rotatable control member is mounted, as shown, adjacent the plunger 45 on a vertical shaft 55 which carries at its lower end, bevel gear 56, meshing with a bevel gear 57 on an adjusting shaft 58 equipped with an adjusting wheel 59 as shown. The said control member comprises a plurality of longitudinally and radially extending guide ribs 60 each having a set of stops 61 slideable thereon and provided with set screws 62 by means of which they may be secured to said ribs in adjusted positions. The arrangement is such that by rotating shaft 55 one of the ribs 60, and the set of stops 62 thereon may be brought into cooperative relationship with the plunger 45 and the stops 50, 51, 52 and 53 on the ends of the operating belts. Each set of stops on each of the ribs 60 is adjusted thereon for corresponding tuning relations of the condensers 14 and the induction coils 34, 35, and 36 so that when the belt stops are in engagement with any one of the sets of stops on the ribs 60, the condensers 14 and the induction coils 34, 35, and 36, the tuning elements of the radio system, will be properly adjusted and connected for the corresponding frequency of the system as will be readily understood by those skilled in the art.

Locking projections 63 are arranged as shown on the under side of the said control member and a notched lock 64 is slidably mounted on the guide post 43 on a sleeve 65 which slidably engages said guide post. A tension spring 66 normally holds the locking member 64 in locking position as indicated.

In use and in operation the various stops 61 are adjusted on the ribs 60 to correspond with the various tuning relations desired between the condensers 14 and the induction coils 34, 35 and 36. When it is desired to change this tuning relation, the push rod 54 is depressed, thus moving all of the tuning elements to predetermined positions and, at the lower end of said movement, depressing the lock 64 to release the shaft 55 for adjustment. While the push rod 54 is held depressed, the adjusting wheel 59 may be manipulated to bring the rib 60, carrying the desired stops 61, into operative position, whereupon the push rod 54 is released. This releases the lock 64 which then rises to lock the shaft 55 in adjusted position and the ends of the adjusting belts rise until their stops engage the said operative stops, thereby limiting the return movements of the tuning elements in proper relation to each other to effect the desired tuning of the system, as will be readily understood by those skilled in this art. In this way, by two simple manipulations, any desired tuning relation may be readily and quickly accomplished. By use of the adjusting belts as shown, the tuning attachments may be readily connected to any established radio system because the belts may be readily extended to any desired positions over suitable guide pulleys. The specific form and arrangement of parts is a simple and effective one for the purpose.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. A radio tuning system comprising a plurality of adjustable tuning elements; means for yieldingly holding said elements in and returning them toward initial positions; flexible operating means for simultaneously moving said elements to predetermined positions and releasing them for return toward said initial positions; a plurality of sets of adjustable stops for said elements; each set arranged to limit the return of said elements in different tuning relations; and means for simultaneously adjusting said sets of stops to effect different tuning relations of said elements.

2. A radio tuning system comprising a plurality of adjustable tuning elements; means for yieldingly holding said elements in and returning them toward initial positions; flexible operating means for simultaneously moving said elements to predetermined positions and releasing them for return toward said initial positions; a plurality of sets of adjustable stops for said elements, each set arranged to limit the return of said elements in different tuning relations; and means, rendered operable by said element moving means for simultaneously adjusting said sets of stops to effect different tuning relations of said elements.

3. A radio tuning system comprising a plurality of adjustable tuning elements; rotatable shafts arranged to adjust said elements; means for yieldingly holding said shafts in and returning them toward initial positions; flexible operating members connected with said shafts for rotating them to adjust said elements; means for simultaneously actuating said flexible members for moving said elements to predetermined positions and releasing them for return toward said initial positions; a stop on each flexible member for limiting its return movement; a plurality of sets of adjustable stops for said stops on said flexible members, each set arranged to limit the return of said elements in different tuning relations; and means for simultaneously adjusting said sets of stops to effect different tuning relations of said elements.

4. A radio tuning system comprising a plurality of adjustable tuning elements; rotatable shafts arranged to adjust said elements; means for yieldingly holding said shafts in and returning them toward initial positions; flexible operating members connected with said shafts for rotating them to adjust said elements; means for simultaneously actuating said flexible members for moving said elements to predetermined positions and releasing them for return toward said initial positions; a stop on each flexible member for limiting its return movement; a plurality of sets of adjustable stops for said stops on said flexible members, each set arranged to limit the return of said elements in different tuning relations; and means, rendered operable by said element moving means for simultaneously adjusting said elements.

5. A radio tuning system comprising a plurality of adjustable tuning elements; rotatable

shafts arranged to adjust said elements; springs yieldingly holding said elements in and returning them toward initial positions; flexible operating members connected with said shafts for 5 rotating them to adjust said elements, the ends of said members being brought together in superposed relation; spaced stops on said flexible members for limiting their return movements; an actuating plunger slidably embracing the ends 10 of said flexible members and provided with cross straps engaging said stops; a plurality of sets of adjustable stops for engaging the stops on said flexible members, each set arranged to limit the return of said elements in different tuning 15 relations; and means for simultaneously adjusting said sets of stops to effect different tuning relations of said elements.

6. A radio tuning system comprising a plurality of adjustable tuning elements; rotatable shafts arranged to adjust said elements; springs yieldingly holding said elements in and returning them toward initial positions; flexible operating members connected with said shafts for 20 rotating them to adjust said elements, the ends of said members being brought together in superposed relation; spaced stops on said flexible members for limiting their return movements; an actuating plunger slidably embracing the ends 25 of said flexible members and provided with cross straps engaging said stops; a plurality of sets of adjustable stops for engaging the stops on said flexible members, each set arranged to limit the return of said elements in different tuning relations; means for simultaneously adjusting said 30 sets of stops to effect different tuning relations of said elements; a lock for said sets of stops; and means, operable by said plunger for releasing said lock.

7. A radio tuning system comprising a plurality of adjustable tuning elements; rotatable shafts arranged to adjust said elements; springs yieldingly holding said elements in and returning them toward initial positions; flexible operating members connected with said shafts for 40 rotating them to adjust said elements, the ends of said members being brought together in superposed relation; spaced stops on said flexible members for limiting their return movements; an actuating plunger slidably embracing the ends of said 45 flexible members and provided with cross straps engaging said stops; a rotatable member having a plurality of longitudinal peripheral guides thereon; a set of stops adjustable on each guide arranged to be rotated into operative relation with the stops on said flexible members to limit the return of said elements in different tuning 50 relations; and a releasable lock for said rotatable member.

8. A radio tuning system comprising a plurality of adjustable tuning elements; rotatable shafts arranged to adjust said elements; springs yieldingly holding said elements in and returning them toward initial positions; flexible operating members connected with said shafts for 55 rotating them to adjust said elements, the ends of said members being brought together in superposed relation; spaced stops on said flexible mem-

bers for limiting their return movements; an actuating plunger slidably embracing the ends of said flexible members and provided with cross straps engaging said stops; a rotatable member having a plurality of longitudinal peripheral guides thereon; a set of stops adjustable on each guide arranged to be rotated into operative relation with the stops on said flexible members to limit the return of said elements in different tuning 10 relations; a releasable lock for said rotatable member; and means operable by said plunger, for releasing said lock.

9. A radio tuning system comprising a plurality of adjustable tuning elements; rotatable shafts arranged to adjust said elements; springs yieldingly holding said elements in and returning them toward initial positions; flexible belt like operating members connected with said shafts for rotating them to adjust said elements, the ends of said members being brought together in superposed relation; spaced stops on said flexible members for limiting their return movements; a longitudinally slidably actuating plunger 15 embracing the ends of said flexible members and provided with cross straps engaging said stops; a rotatable member arranged adjacent said plunger and provided with a plurality of radiating ribs having their outer ends formed into longitudinal peripheral guides; a set of stops longitudinally adjustable on each of said ribs and arranged to be moved in and out of operative relation with the stops on said flexible members to limit the return of said elements in different tuning 20 relations; and a releasable lock 25 for said rotatable member.

10. A radio tuning system comprising a plurality of adjustable tuning elements; rotatable shafts arranged to adjust said elements; springs yieldingly holding said elements in and returning them toward initial positions; flexible belt like operating members connected with said shafts for 30 rotating them to adjust said elements, the ends of said members being brought together in superposed relation; spaced stops on said flexible members for limiting their return movements; a longitudinally slidably actuating plunger 35 embracing the ends of said flexible members and provided with cross straps engaging said stops; a rotatable member arranged adjacent said plunger and provided with a plurality of radiating ribs having their outer ends formed into longitudinal peripheral guides; a set of stops longitudinally adjustable on each of said ribs and arranged to be moved in and out of operative relation with the stops on said flexible 40 members to limit the return of said elements in different tuning relations; a plurality of spaced locking projections on the end of said rotatable member adapted and arranged to lock the same in its different positions of adjustment; and a 45 spring held lock arranged to releasably engage said locking projections and adapted and arranged to be engaged by said plunger at the end of its operative movement to release said rotatable member for adjustments thereof.
